Primary Examiner—Robert M. Spear
Attorney, Agent, or Firm—Kubovcik & Kubovcik**CLAIM**

The ornamental design for a diamond abrasive saw blade, as shown and described.

DESCRIPTION

FIG. 1 is a front view of the diamond abrasive saw blade; FIG. 2 is a top view of the diamond abrasive saw blade, the bottom view being identical thereto; FIG. 3 is a side view of the diamond abrasive saw blade, the opposite side view being a mirror image thereof; FIG. 4 is a cross-section of the diamond abrasive saw blade taken along 4—4 in FIG. 1;

FIG. 5 is an enlarged view of part 5—5 of the cross-section of the diamond abrasive saw blade shown in FIG. 4 and shows the electrodeposited diamonds on the periphery of the saw blade;

FIG. 6 is an enlarged view of part 6—6 of the cross-section of the diamond abrasive saw blade shown in FIG. 4 and shows the electrodeposited diamonds on the periphery of the saw blade; and,

FIG. 7 is a rear view of the diamond abrasive saw blade.
